CLAIM

The ornamental design for a racquetball racquet, as shown and described.

DESCRIPTION

FIG. 1 is a front elevational view of a racquetball racquet showing my design, the rear elevational view being a mirror image;

FIG. 2 is a left side elevational view thereof;

FIG. 3 is a right side elevational view thereof;

FIG. 4 is a top plan view thereof; and,

FIG. 5 is a bottom plan view thereof.
